SOUND ABSORBING CONSTRUCTION

Lionel H. MacDonald, Kansas City, Mo., assignor
of forty-five per cent to H. Kenneth Taylor

Application January 6, 1936, Serial No. 57,690

8 Claims. (Cl. 189—85)

This invention relates to sound-absorbing construction of a type consisting of juxtaposed foraminous diaphragms supportingly facing sound-absorbing material and employed as a lining or covering for the walls and ceilings of auditoriums, theatres, offices and other rooms for improving acoustical conditions therein.

The principal object of the present invention is to provide a cover or presentable finished surface of this character wherein the diaphragms are readily fabricated and capable of being quickly installed in such a manner that the exposed faces thereof are assured of being located in the same common plane after installation is completed.

Other important objects of the invention are to provide a diaphragm construction wherein the attaching means is concealed, to provide a substantially flexible diaphragm construction which does not resist movement responsive to sound waves, to provide a cover which when assembled has the appearance of tiling or sheets, etc., to provide for attaching the diaphragms without the use of screws, bolts, or other threaded fastening devices, and to provide a construction wherein the sound-absorbing material does not interfere with painting of the diaphragms or the paint with the absorbing qualities of the material.

In accomplishing these and other objects of the invention, as hereinafter pointed out, I have provided improved details of structure the preferred forms of which are illustrated in the accompanying drawings wherein:

Fig. 1 is a perspective view of a portion of a ceiling equipped with a sound-absorbing structure embodying the features of the present invention, a part of one of the diaphragm units being broken away to better illustrate its construction.

Fig. 2 is a section through the sound-absorbing structure at a point adjacent one of the side walls.

Fig. 3 is a detail section taken at right angles to the section shown in Fig. 2.

Fig. 4 is a detail perspective view of one of the diaphragm units prior to insertion of the sound-absorbing material.

Fig. 5 is a detail perspective view of a portion of one of the furring strips to which the diaphragm units are attached.

Fig. 6 is a detail perspective view showing a modified form of flange construction for the diaphragm unit.

Fig. 7 is a detail perspective view of a modified form of diaphragm unit.

Fig. 8 is a vertical section through a sound-absorbing structure employing the diaphragm unit shown in Fig. 7.

Fig. 9 illustrates a modified form of furring strips as used in connection with the diaphragm units illustrated in Fig. 7.

Fig. 10 is a further modified form of diaphragm.

Fig. 11 is a detail section through a sound-absorbing structure employing the diaphragm unit shown in Fig. 10.

Referring more in detail to the drawings:

1 designates a sound-absorbing structure as applied to the ceiling 2 of a room, and which includes a plurality of juxtaposed foraminous diaphragm units 3 that are supported in spaced relation to the ceiling 2 by means of furring strips 4, later described. The units 3 are preferably constructed of relatively thin gauge sheet material capable of being self-supporting when formed into a completed unit. The unit 3 includes a flat rectangular diaphragm portion 5, having a plurality of apertures 6 to form a foraminous surface capable of movement responsive to sound waves and to permit sound energy to pass through the unit.

The side and end edges of the diaphragm are broken upwardly and outwardly, as at 7, at an angle to the foraminous portion, and then upwardly, as at 8, to form bevelled edges and lateral side flanges 9—10 and end edges 11—12. If desired, the intermediate portion of the diaphragm may be provided with a V-shaped groove 13 which cooperates with the bevelled edges of the unit to assimilate tiling when the units are connected in juxtaposed assembly, as later described.

The side flanges 9 and 10 and the end flange 12 are of sufficient depth to enclose a sheet of sound-absorbing material 14, but the end flange 11 is of slightly greater depth and terminates in a lateral attaching flange 15 having spaced slotted openings 16 and 17 adjacent the ends thereof.

The end flange 11 also has spaced slotted openings 18 and 19 located substantially midway the height thereof and which may be located in approximate alignment with openings 16 and 17. The opposite end flange 12 has outstruck tongues or lips 20 and 21 which align with and are adapted to engage in the slots 18 and 19 of an adjacent unit as later described, the tongues 20 and 21 being located at a sufficient height relatively to the slots 18 and 19 that the lower faces of the diaphragms will align in the same plane when the units are juxtaposed.

The apertures 8 may be of various size and arrangement, however they are of sufficient number to provide ample passage of the sound energy to the sound-absorbing material, but are of such a size as to prevent clogging by paint or other decorative effects applied to the exposed surface of the diaphragm as in customary practice.

In order to space the sound-absorbing material from contact with the inner surface of the diaphragm, the flanges thereof may be provided with spaced instruck lips 22 for supporting the edges of the sound-absorbing material. This is an important feature, particularly in the case where hairy or felt-like sound-absorbing material is employed, as it prevents the strands thereof from projecting through the perforations to interfere with painting, and prevents the paint from coating any of the sound-absorbing surfaces of the material 14.

The diaphragm units thus constructed are of sufficient rigidity to be, in themselves, self-supporting, but they have maximum flexibility to allow movement responsive to sound waves to thereby enhance their sound-absorbing and deadening qualities when used in connection with the sound-absorbing material.

The sound-absorbing material 14 may be of any suitable nature, but is preferably of sheet or pad form so that it is self-supporting when seated upon the instruck lips 22 of the diaphragm.

The furring strips 4 are preferably of structural shapes, for example those illustrated in Figs. 1, 2 and 5 are of I-beam cross section and are formed of a single sheet metal strip bent 35 to provide horizontal flanges 23 and 24 and a connecting web 25. One of the wings 26 of the horizontal flange 24 is cut outwardly at spaced points along the length thereof to provide tongues 27 having substantially the same length as the 40 width of the slots 16 and 17, the tongues being bent downwardly below the lower face of the flange to form keeper loops through which a fastening device, such as a nail or pin 28, may be extended to secure the attaching flanges 15 of the diaphragm units, as illustrated in Figs. 1, 2 and 3.

The spacing of the slots 16 and 17 relative to the widths of the units and to each other are such that when the units are placed in juxtaposed position the loop-shaped tongues will be 50 equally spaced along the length of the furring strip flange.

In assembling a sound-absorbing structure employing the form of the invention illustrated in Figs. 1 to 5 inclusive, and in a room requiring acoustical correction, the furring strips may be applied to the ceiling 2 by passing toggle bolts 29, or similar fastening devices, through suitable openings 30 in the flanges 23 of the furring strips, and to the building structure as shown in Fig. 2, the furring strips being so spaced in parallel relation that they will correspond to the length of the diaphragm units. The diaphragms are then assembled with the sound-absorbing material seated therein. The assembly may be started at various points, for example a cove moulding 31 may be applied along one side of the wall of the room at a distance spaced from the lower flanges of the furring strips so 60 that when the attaching flanges of the units engage with the adjacent furring strip and the opposite end of the unit is supported on the cove, the units will be in horizontal position. A row of units is then assembled in side to side contact with the ends carrying the flanges 12 seated

upon the cove strip and the attaching flanges 15 engaging the under face of the furring strip so that the loop tongues thereon project through the openings 16 and 17. Suitable nails or pins 28 are then inserted through the projecting portions of the loops to engage the under faces of the attaching flanges, as best illustrated in Fig. 3. The units are thus keyed to the furring strips without bolts, screws or other threaded fastening devices, and are readily applied without the use of tools.

After the first row of units is installed, the next row is applied by inserting the tongues 28 and 29 thereof into the openings 16 and 17 that are provided in the flanges 11 of the units already in place. When the tongues 28 and 29 are thus engaged, the lower faces of the units will align in the same plane. The tongues thus support one end of the next row of units from the units already in place, and the opposite ends of the units are keyed to the next adjacent furring strip by inserting the pins 28 through the projecting portions of the loop-shaped tongues. The structure is thus built up until the ceiling is completely covered, after which cove strips 31 are applied to the remaining side and end walls of the room.

The units, when thus installed, have the appearance of block-shaped tiles and may be painted or decorated in any suitable manner without interfering with their sound-absorbing properties.

When the sound-absorbing structure is to be installed in a new building, the furring strips may be incorporated as a part of the building structure, and so spaced that they will conform to the size of the sound-absorbing units.

In Figs. 6, 7 and 8 is shown a modified form of unit wherein the attaching flange 32 forms a continuation of a corresponding end flange 33, and is provided with rectangular shaped openings 34 and 35 corresponding to the openings 16 and 17 described in connection with the preferred form of the invention.

The lower portion of the end flange 33 is provided with openings 36 and 37, corresponding to the openings 16 and 17 previously described, and which are engaged by tongues 38 and 39 on the opposite end flange 40 of an adjacent unit. The furring strips 41 are shown as comprising T-shaped members having attaching flanges 42 and a depending web 43 provided with instruck loop-shaped tongues 44 so that when the units are assembled with the flanges 32 engaging against the sides of the depending 55 webs 43, the tongues will pass through the openings 34 and 35 to be keyed by pins 45. The construction is otherwise substantially the same as that shown in the preferred form of the invention.

In Figs. 8 and 9 is shown a further modified form of diaphragm unit, wherein the unit comprises a foraminated sheet of fibre, fabric, composition board, metal, or the like 46, to one edge of which are secured substantially Z-shaped 65 clips 47 and 48 having flanges 49 that are riveted or otherwise attached to the diaphragm, and anchoring flanges 50 that are connected thereto by webs 51. The anchoring flanges 50 have openings 52 for engaging the loop-shaped 70 tongues of the furring strips in the same manner as the preferred form of the invention, and the webs have openings 53 for engaging the tongues 54 of clips 55 that are riveted or otherwise attached to the opposite edge of the dia- 75

phragm. In this form of the invention the sound-absorbing material 56 may be supported directly on the upper faces of the diaphragm sheets as shown in Fig. 10, or spaced therefrom by suitable spacers (not shown).

5 The form of tongue shown in Fig. 6 is substantially the same as that in the preferred form of the invention, however the tongue 57 is struck from within the body of the end flange 10 so that the upper edge 58 thereof is continuous across the width of the unit.

10 From the foregoing it is obvious that I have provided a sound-absorbing structure wherein the units are readily assembled in juxtaposed 15 position, and that when the units are installed the lower faces thereof automatically align in the same common plane. While I have particularly illustrated and described my invention as being applied to a ceiling structure, it is obvious that 20 it may be applied to the walls or other parts of the building without departing from the spirit of the invention.

25 What I claim and desire to secure by Letters Patent is:

25 1. In a sound-absorbing construction of the character described, spaced furring strips having projecting loop portions, a plurality of juxtaposed foraminous diaphragms, a sheet of sound-absorbing material supported by and covering each diaphragm, flanges on the diaphragms having tongues and slots respectively whereby the tongues on one diaphragm engage in the slots of an adjacent diaphragm, one of said flanges extending between adjacent sheets of sound-absorbing material and projecting therefrom in the direction of the furring strips, attaching flanges on the projecting flanges and having openings for engaging the projecting loop portions of the furring strips, and pins extended through said 40 loop portions for supporting the diaphragms.

45 2. In a sound-absorbing construction of the character described, spaced furring strips having projecting loop portions, a plurality of juxtaposed foraminous diaphragms, attaching flanges on the diaphragms and having openings for engaging over the projecting loop portions of the furring strips, and means extended through said loop portions for supporting the diaphragms on the furring strips whereby said diaphragms have direct 50 connection with the furring strips.

55 3. In a sound-absorbing construction of the character described, spaced furring strips having projecting loop portions, a plurality of juxtaposed foraminous diaphragms, flanges on the diaphragms having tongues and slots respectively whereby the tongues on one diaphragm engage in the slots of an adjacent diaphragm one of said flanges having openings projecting over the projecting loop portions of the furring strips, and pins extending through said loop portions for directly keying each diaphragm to a furring strip.

60 4. In a sound-absorbing construction of the character described, spaced furring strips having projecting loop portions, a plurality of juxtaposed diaphragms, means extending through said loop

portions and engaging portions of the diaphragms for keying the diaphragms to the furring strips, and sheets of sound-absorbing material supported above the diaphragms and underlying the furring strips to insulate transmission of external sound through the furring strips to the diaphragms.

5 5. In a sound-absorbing construction of the character described, spaced furring strips having projecting loop portions, a plurality of juxtaposed foraminous diaphragms, clips on the diaphragms having tongues and slots respectively whereby the tongues on one diaphragm engage in the slots of an adjacent diaphragm one of said clips having openings extending over the loop portions of the furring strips, and pins extending through said loop portions for keying the diaphragms to the furring strips.

10 6. In a sound absorbing construction of the character described, spaced furring members, a plurality of juxtaposed foraminous diaphragms, a sheet of sound absorbing material supported by and covering each diaphragm, slotted flange members on one edge of the diaphragms and extending between adjacent sheets of sound absorbing material in the direction of the furring members, tongues on opposite edges of the diaphragms arranged to engage in the slotted flange members of an adjacent diaphragm, one of said members having projecting loop portions and the other openings for engaging the projecting loop portions, and means extended through said loop portions for supporting the diaphragms.

15 7. In a sound absorbing construction of the character described, spaced furring strips having projecting loop portions, a plurality of juxtaposed foraminous diaphragms, a sheet of sound absorbing material supported by and covering each diaphragm, clips fixed to the respective edges of the adjacent diaphragms and having tongues and slots respectively whereby the tongues on the clips carried by one diaphragm engage in the slots of the clips carried by an adjacent diaphragm, one of said clips having a portion extending between adjacent sheets of sound absorbing material and terminating in attaching flanges having openings engaging the projecting loop portions of the furring strips, and pins extended through said loop portions for supporting said diaphragms.

20 8. In a sound absorbing construction of the character described, spaced furring members, a plurality of juxtaposed foraminous diaphragms, a sheet of sound absorbing material supported by and covering each diaphragm, clips fixed to the respective edges of adjacent diaphragms and having tongues and slots respectively whereby the tongues on the clips carried by one diaphragm engage in the slots of the clips carried by an adjacent diaphragm, one of said clips having an attaching flange member, one of said members having openings and the other projecting loop portions engaging within the openings, and pins extending through the loop portions for suspendingly supporting the diaphragms.

25 LIONEL H. MACDONALD. 65
